(57) **CLAIM**

The ornamental design for a clip for a sensor probe, as shown and described.

DESCRIPTION

FIG. 1 is a first perspective view of a clip for a sensor probe. FIG. 2 is a second perspective view of the clip of FIG. 1 rotated counterclockwise.

FIG. 3 is a front view of the clip of FIG. 1.

FIG. 4 is a rear view of the clip of FIG. 1.

FIG. 5 is a right view of the clip of FIG. 1.

FIG. 6 is a left view of the clip of FIG. 1.

FIG. 7 is a top view of the clip of FIG. 1.

FIG. 8 is a bottom view of the clip of FIG. 1.

FIG. 9 is a cross-sectional bottom view of the clip of FIG. 1. The cross-sectional view is along the line 9-9 of FIG. 3; and,

FIG. 10 is a cross-sectional right view of the clip of FIG. 1. The cross-sectional view is along the line 10-10 of FIG. 3.
